UNITED STATES PATENT OFFICE

BURKE BRADBURY, OF SCHENECTADY, NEW YORK, ASSIGNOR TO GENERAL ELECTRIC COMPANY, A CORPORATION OF NEW YORK

AMPLIFYING SYSTEM

Application filed April 7, 1928. Serial No. 268,356.

The present invention relates to amplifying systems, and more particularly to systems employing electron discharge apparatus for the amplification of high frequency currents.

5 In amplifying systems involving the use of the three-electrode, electron discharge devices it has been proposed to tune the output circuit for the purpose of obtaining selectivity, but this method of obtaining selectivity has not been generally used because of the fact that the output impedance of the device is low enough to reduce greatly the sharpness of the tuning which can be obtained. The use of a resonant output circuit also tends to the production of oscillations because of the feed-back through the device due to the capacity between the grid and plate electrodes.

10 To avoid these disadvantages it has become customary to use an untuned output circuit loosely coupled by a step-up transformer to a tuned input circuit of the succeeding device. By this expedient the effect of the 15 output impedance of the device in decreasing the sharpness of the tuning has been very greatly decreased and at the same time the tendency to oscillate has been decreased.

It is known that with a four-element electron discharge device having two grids, one 20 of which serves to screen the plate and control grid to eliminate the effect of capacity coupling between the two the plate or output impedance is many times greater than that 25 of an ordinary three-element device. Because of this difference in the output impedance it has been proposed to provide a tuned output circuit for the device as good selectivity may be obtained by this expedient, 30 and at the same time the tuned output circuit provides a high external impedance in the output circuit which is conducive to efficient operation. This arrangement however has the disadvantage that where the system is 35 employed for operation over a wide range of

frequencies the impedance of the tuned output circuit will vary considerably over the range of frequencies to be used and hence uniform amplification cannot be obtained over the entire frequency range.

The object of my invention is to provide a circuit arrangement which will overcome this disadvantage, which will furnish sufficiently high output impedance to insure a high degree of amplification and which at the same time will give a substantially uniform degree of amplification over the entire operating range of the apparatus.

In carrying my invention into effect I provide tuned input circuits for one or more electron discharge amplifiers and closely couple these tuned input circuits by transformers to the untuned output circuits of the preceding four electrode screen grid electron discharge devices.

I have found that these transformers may to advantage have a one to one ratio of turns, or may even have a greater number of turns in the primary winding than in the secondary. With this expedient the effective impedance 70 of the output circuit of the four-electrode device may be made substantially as high or even higher than would be the case if the output circuit itself were tuned. Where a greater number of primary than secondary turns are 75 employed the effective impedance of the output circuit may be made somewhat higher than if the ratio were held at one to one and this may in some cases appreciably increase the degree of amplification obtained as the 80 plate impedance of the four-element tube is ordinarily considerably higher than the impedance at resonance of a well designed parallel tuned circuit, and it is well known that for the maximum degree of amplification the 85 output impedance of the circuit should be substantially equal to the tube impedance.

I have also found that by suitable separation of the secondary and primary of the transformer the capacity between the wind- 90

ings may be so adjusted by proper selection of the spacing between them, that the transfer of voltage from primary to secondary will be substantially uniform over the entire operating range of frequencies. For example, the following measurements were made on a transformer with only one layer of .0025" paper between the windings.

Capacity between windings--- 466 m. m. f.
Coefficient of coupling----- 99.4%

Frequency	Amplification
600 K. C.	23.5
1000 K. C.	31.5
1400 K. C.	36.0

In comparison with this another transformer was wound with .020" of paper insulation between windings and the measurements were as follows:

Capacity between windings--- 106 m. m. f.
Coefficient of coupling----- 93.2%

Frequency	Amplification
600 K. C.	27
1000 K. C.	30
1400 K. C.	29

In the latter case it will be noticed that the capacity between windings has decreased much faster than the coupling coefficient, thus reducing the degree of amplification at the higher frequencies where the capacity coupling is most effective. This reduction in coupling naturally improves the selectivity over what it would be with tight coupling.

I have also found that the selectivity may still further be improved, with uniform amplitude of amplification, by reversing the polarity of one winding with respect to the other, as for example, by winding one coil in the opposite direction from the other. In any case, adjacent ends of the two windings should be at the same potential with respect to ground, high or low, as the case may be. When wound in opposite directions the natural capacity coupling is in opposite phase to the magnetic coupling of the coils and the spacing between them must be somewhat greater than when wound in the same direction to prevent the two sources of coupling from bucking each other to nearly zero effective coupling at the high frequency end of the range. The greater spacing reduces the capacity coupling so that the magnetic coupling predominates by an amount sufficient to produce a substantial degree of amplification at an amplitude which remains practically constant over the entire operating range. Improvement in selectivity is obtained in this case by reason of the greater separation of the windings.

The novel features which I believe to be characteristic of my invention are set forth with particularity in the appended claims; the invention itself, however, both as to its organization and method of operation will

best be understood by reference to the following description taken in connection with the accompanying drawing in which Figs. 1 and 2 show diagrammatically two different circuit organizations in which my invention is carried into effect.

I have shown in Fig. 1 a receiving system comprising a screen grid radio frequency amplifier device 1, a regenerative detector 2, and two audio frequency amplifying devices 3 and 4. Signaling currents received upon the antenna 5 are impressed by means of the coupling transformer 6 upon the tuned input circuit 7 of device 1. The output circuit of device 1 is coupled by means of the coupling transformer 9 through the tuned input circuit 10 of the regenerative detector 2. The output of the circuit of the detector is coupled by means of the transformer 11 to the input circuit of the audio amplifier 3. Coupling transformer 9 is constructed in accordance with the principles which I have described above so as to give a substantially uniform degree of amplification over the entire range over which the receiving set is intended to operate.

In the arrangement shown in Fig. 2, 3 stages of tuned radio frequency amplification employing three electron discharge devices of the screen grid type, 12, 13 and 14, are provided. The coupling transformers 15, 16 and 17, may all be of the special construction which I have described for giving substantially uniform amplification over the entire operating range.

To prevent stray coupling between the different tuned circuits the various screen grid devices and circuits are enclosed in grounded shields as indicated, or separated by grounded shields, as shown by dotted lines in the two figures of the drawing. In the arrangement shown in Fig. 2, the desired operating potential for screening grids 18 is provided by means of suitable source connected to terminals 19 and 20. By controlling this potential by means of potentiometer arrangement 21, a convenient and satisfactory volume control of the degree of amplification is provided. This, however, is not a part of my present invention, but is described and claimed in a pending application of C. M. Burrill, and assigned to the same assignee as the present application.

In the system shown in Fig. 1, volume control is accomplished by means of the variable resistance 22 which is inserted in the cathode circuit of amplifier 1.

While I have shown and described only two different circuit organizations in which my invention is employed it will be evident that many modifications in the circuit arrangements and the specific design of the coupling transformers may be made without departing from the scope of my invention as set forth in the appended claims.

What I claim as new and desire to secure by Letters Patent of the United States, is:—

1. The combination in an amplifying system of a four-electrode screen-grid electron discharge device having a tunable input circuit and an output circuit, means for impressing currents to be amplified on the input circuit, and a transformer having a primary winding in the output circuit and a secondary winding connected in the tunable input circuit of a second electron discharge device, said transformer having substantially as great a number of primary turns as secondary turns, the polarity of the secondary winding being reversed with respect to that of the primary winding and said windings being spaced to provide a natural capacity coupling between them which transfers energy in opposite phase to that transferred by the magnetic coupling existing between said windings and to such an extent that a substantially uniform voltage amplification is produced over the entire frequency range over which the said input circuit is tunable. 70
- 10 2. The combination in an amplifying system of a four-electrode screen-grid electron discharge device having a tunable input circuit and an output circuit, means for impressing currents to be amplified on the input circuit, and a transformer having a primary winding in the output circuit and a secondary winding connected in the tunable input circuit of a second electron discharge device, said transformer having substantially as great a number of primary turns as secondary turns, the primary turns being closely coupled electromagnetically to the secondary turns and the primary and secondary turns being separated to such an extent by an intervening dielectric 85 that the combined electromagnetic and electrostatic couplings serve to produce substantially uniform voltage amplification over the entire frequency range over which the system is adapted to operate. 90
- 15 3. The combination in an amplifying system of a four-electrode screen-grid electron discharge device having a tunable input circuit and an output circuit, means for impressing currents to be amplified on the input circuit, and a transformer having a primary winding in the output circuit and a secondary winding connected in the tunable input circuit of a second electron discharge device, said transformer having substantially as great a number of primary turns as secondary turns, the polarity of the secondary winding being reversed with respect to that of the primary winding and said windings being spaced to provide a substantially uniform transfer of voltage between them over a range of frequencies to which said input circuit is tunable. 95
- 20 4. The combination in an amplifying system of a four-electrode screen-grid electron discharge device having a tunable input circuit and an output circuit, means for impressing currents to be amplified on the input circuit, and a transformer having a primary winding in the output circuit and a secondary winding connected in the tunable input circuit of a second electron discharge device, said transformer having substantially as great a number of primary turns as secondary turns, said windings being so related that the natural capacity coupling between primary and secondary transfers energy in opposite phase to that transferred by the magnetic coupling 100 and to such an extent that a substantially uniform voltage amplification is produced over the entire range over which the said input circuits are tunable. 105
- 25 5. The combination in an amplifying system adapted to operate over a predetermined range of radio frequencies of a plurality of electron discharge devices having tunable input circuits and a coupling transformer connecting the output circuit of one device to the input circuit of another device, said transformer having substantially as great a number of primary turns as secondary turns, the primary turns being closely coupled electromagnetically to the secondary turns and the primary and secondary turns being separated to such an extent by an intervening dielectric 110 that the combined electromagnetic and electrostatic couplings serve to produce substantially uniform voltage amplification over the entire frequency range over which the system is adapted to operate. 115
- 30 6. The combination in an amplifying system adapted to operate over a predetermined range of radio frequencies of a plurality of electron discharge devices having tunable input circuits and a coupling transformer connecting the output circuit of one device to the input circuit of another device, said transformer having substantially as great a number of primary turns as secondary turns, the primary turns being closely coupled electromagnetically to the secondary turns and the polarity of the secondary winding being reversed with respect to that of the primary winding, and the primary and secondary turns being separated to such an extent by an intervening dielectric 120 that the combined electromagnetic and electrostatic couplings serve to produce substantially uniform voltage amplification over the entire frequency range over which the system is adapted to operate. 125
- 35 In witness whereof, I have hereunto set my hand this 6th day of April, 1928.
- BURKE BRADBURY. 130
